UNITED STATES PATENT OFFICE.

HARVEY S. BRISTOL, OF CHICAGO, ILLINOIS.

CONTROLLING DEVICE FOR MOTORS.

SPECIFICATION forming part of Letters Patent No. 674,643, dated May 21, 1901.

Application filed December 28, 1896. Serial No. 617,161. (No model.)

To all whom it may concern:

Be it known that I, HARVEY S. BRISTOL, a citizen of the United States, residing at Chicago, in the county of Cook and State of Illinois, have invented certain Improvements in Controlling Devices for Motors, of which the following is a specification.

My invention relates to controlling devices for motors, and has for its object to provide a new and improved controlling device, of which the following is a description, reference being had to the accompanying drawings, wherein—

Figure 1 is a plan view of a controlling device embodying my invention. Fig. 2 is a section on line 2 2, Fig. 1. Fig. 3 is a section on line 3 3, Fig. 2. Fig. 4 is a section on line 4 4, Fig. 2, with parts omitted. Fig. 5 is a detail view of the power-transmitting shaft.

Like letters refer to like parts throughout the several figures.

My controlling device may be used in connection with any kind of a motor and in connection with any mechanism which such motor may be used to operate.

The power-transmitting shaft A is operatively connected with the motor in any desired manner and is provided with cranks B, C, and D. I have shown this shaft with three cranks; but I may use any number of cranks desired. When the three cranks are used, I prefer to place these cranks one hundred and twenty degrees apart. These cranks are each associated with a link B' C' D', said links being mounted at their upper end upon the shaft E. These links are provided with the slots A', and the crank-pins A² pass through said slots. Said links are also provided with the slots A³, in which work the sliding blocks A⁴, to which are pivotally connected the arms B². A series of downwardly-projecting arms B³ are also pivotally connected with said blocks, said latter arms being connected with the arms B⁴, which are preferably rigidly connected to the rock-shaft E'. A lever E² is connected to said shaft and is provided with a rack E³ and a locking device E⁴, so that its position can be varied. The movement of this lever E² varies the position of the sliding blocks A⁴. The rods B² are pivotally connected in any desired manner to the gripping-plates F, associated with

the wheels or disks F', rigidly connected to the shaft F². These gripping-plates F are preferably constructed as shown, and consist of a body portion having the gripping ends F³ F⁴, which engage the flanges or rims of the wheels F'. These flanges or rims are preferably beveled at F⁵, as shown in Fig. 3, the gripping ends of the plate F being beveled in a similar manner. The lower end of the plate is provided with two projecting ends F⁶ F⁷, which project downwardly, one on each side of the shaft F². The distance between these ends is greater than the diameter of the shaft, so that the plate can be moved relative to said shaft. A key F⁸ passes through each of said gripping-plates and engages the shaft F², being preferably held in place by the screw F⁹. This key allows the mechanism to be adjusted for wear. Connected to each one of the locking-plates is a rod G, which passes through a sleeve G', connected to a projecting arm on the shaft G². I prefer to construct this arm as shown in Fig. 4 and provide it with the two branches G³, the sleeve G' being located between said branches and being held in place by the screws G⁴. Located on each side of the sleeve G' are the springs G⁵ G⁶, one end of each spring engaging the sleeve, the other end of said springs engaging suitable stops. The shaft G² is provided with the controlling-lever H, by which its position may be varied, said controlling-lever being provided with some suitable locking device by which it may be held in any desired position. I prefer to form the wheels F' as shown in Fig. 3, so that they have a projecting hub F¹⁰, so that they can be connected to the shaft F² by means of a set-screw. I have shown only three wheels and accompanying parts; but it is of course evident that any greater number may be used, if desired; but I do not think it necessary to show more than three. Instead of using the cranks B, C, and D, I may of course use the ordinary eccentrics; but I prefer to use the cranks, because they occupy less space. The several shafts are of course mounted in suitable bearings, and the device to be driven by the motor is connected with the shaft F². I have described these several parts in detail; but it is evident that they may be varied in form, construction, and arrangement without de-

parting from the spirit of my invention, and I therefore do not wish to be limited to the construction shown and described.

The use and operation of my invention are as follows: When it is desired to transmit power from a motor to a driven device, the motor is connected with the shaft A and the driven device with the shaft F². When this is done, the driven device may be stopped and started and driven at any desired speed without in any manner controlling the motor, said motor running at full speed all the time. It is very desirable to produce this effect in many mechanisms—as, for example, in the use of gas-engines when used to drive horseless vehicles or when used for any other purpose, as such engines are not efficient at the start and are only able to do good work when run continuously. When it is desired to operate the driven device, the sliding blocks A are moved toward the lower end of their slots by means of the lever E², shaft E', and arms B³ B⁴, &c. As the driven shaft A rotates the cranks rock the links B', C', and D', thereby reciprocating the arms or rods B². The movements of these rods cause the gripping-plates to move and one of the gripping ends F³ or F⁴ to engage the periphery or rim of said wheels and rotate same. If, for example, the parts are in the position shown in Fig. 2, the gripping end F³ will come in contact with the rim of the wheel as the arm B² is moved outwardly and rotate said wheel in the direction of the arrow. As the cranks of the shaft A rotate the rod B² will be moved backwardly and the gripping end F³ disengaged from the wheel, thereby allowing the gripping-plate to be moved back to its operative position. Since the cranks are situated one hundred and twenty degrees apart, the other gripping-plate, or at least one of them, is being moved in an opposite direction, while the plate connected with the rod B² is being moved toward its operative position, thereby producing a continuous movement of the shaft F². It will be seen that the throw or distance of movement of the arms B², &c., is controlled by the position of the sliding blocks A⁴, and hence the speed of the driven shaft or driven device is easily controlled by moving these sliding blocks through the agency of the controlling-lever E². If said blocks are moved to the upper ends of the slots A³, there will be no reciprocating movement of the arms B², for example, and hence the driven shaft or driven device will remain stationary. The motion of the driven shaft can be reversed by moving the lever H. If said lever is moved in the direction of the arrow, (see Fig. 3,) the several gripping-plates through the agency of the rods G and associated parts will be moved so that the shaft F² will be nearest the projecting arm F⁷. When in this position the gripping end F³ will be free, while the gripping end F⁴ will be in operative connection

with the wheel, and hence the motion of said wheel will be reversed.

It will therefore be seen that I have here a controlling device for motors by which the driven device may be stopped or started or operated at any desired speed while the motor is running continuously and at a uniform speed, therefore controlling the driven mechanism independent of the motor. 75

I claim—

1. A controlling device for motors comprising a driving-shaft, a series of arms connected with said shaft so as to be reciprocated thereby, a driven shaft, a series of wheels or disks connected therewith, a gripping-plate F associated with each of said disks, said gripping-plates operatively connected with said reciprocating arms, each gripping-plate provided with two gripping ends F³ and F⁴ 85 and associated with said shaft so as to be free to move laterally with relation thereto, a controlling-lever H operatively connected with said gripping-plates so as to shift their position with relation to said shaft when operated and move one or the other of said gripping ends into operative relation with the rim of the wheel. 90

2. A controlling-lever for motors, comprising a driving-shaft having a series of cranks connected therewith, a link associated with each of said cranks so as to be oscillated thereby, a sliding block associated with each link, a controlling-lever E² connected with each sliding block, by which the position of said blocks may be controlled, a driven shaft F², a series of disks F' associated therewith, a gripping-plate F associated with each disk and provided with gripping ends F³ and F⁴, 100 said disks provided with beveled faces F⁵, 105 said gripping ends adapted to alternately grip and release said beveled face when the gripping-plate is moved, and a connection between each gripping-plate and one of said sliding blocks, substantially as described. 110

3. A controlling device for motors, comprising a driving-shaft having a series of cranks connected therewith, a link associated with each of said cranks so as to be oscillated thereby, a sliding block associated with each link, a controlling-lever connected with each sliding block whereby their position may be controlled, a driven shaft, a series of disks or wheels associated therewith, a gripping-plate F associated with each of said disks or wheels 115 and adapted when moved to alternately grip and release the rim of said wheels, a connection B² between each gripping-plate and one of said sliding blocks, said gripping-plates so constructed as to be capable of lateral motion 120 with relation to said driven shaft and being provided with two gripping ends, one adapted to operate when the plate is in one position and the other adapted to operate when the gripping-plate is in a different position, 125 a connection G between each of said gripping-plates and a controlling-lever H, where- 130

by their position may be changed so as to reverse the motion of said driven shaft.

4. A controlling device for motors, comprising a driving-shaft having a series of cranks connected therewith, a link associated with each of said cranks so as to be oscillated thereby, a sliding block associated with each link, a controlling-lever connected with each sliding block, whereby their position may be controlled, a driven shaft, a series of disks or wheels associated therewith, a gripping-plate F associated with each of said disks or wheels and adapted when moved to alternately grip and release the rim of said wheels, a connection B² between each gripping-plate and one of said sliding blocks, said gripping-plates so constructed as to be capable of lateral motion with relation to said driven shaft and being provided with two gripping ends, one adapted to operate when the plate is in one position and the other adapted to operate when the gripping-plate is in a different position, a rod G connected to each of said gripping-plates and elastically connected with a controlling-lever H so that the position of said plates may be shifted by the position of said lever, said plates being elastically held in their desired position.

5. A controlling device for motors comprising a driving-shaft, having a series of cranks connected therewith, a link associated with each of said cranks so as to be oscillated thereby, a sliding block associated with each link, a controlling-lever connected with each sliding block whereby their position may be controlled, a driven shaft, a series of disks or wheels associated therewith, a gripping-plate F associated with each of said disks or wheels and adapted when moved to alternately grip and release the rim of said wheels, a connection B² between each gripping-plate and one of said sliding blocks, said gripping-plates so constructed as to be capable of lateral motion with relation to said driven shaft and being provided with two gripping ends, one adapted to operate when the plate is in one position

and the other adapted to operate when the gripping-plate is in a different position, a rod or arm G connected with each of said gripping-plates, a sleeve through which the said rod or arm passes, a rock-shaft G² connected with said sleeve, a spring G⁵ G⁶ on each side of said sleeve and connected with said rod, a controlling-lever H connected with said rock-shaft, the whole so arranged that said gripping-plates may be shifted by a movement of said lever.

6. A controlling device for motors, comprising a driving-shaft, a series of cranks associated with said shaft, a series of pivoted links connected with said cranks so as to be operated thereby when the shaft is rotated, a sliding block associated with each link, a controlling-lever connected with each sliding block by which their position is varied, a driven shaft, a series of disks or wheels connected therewith, a gripping-plate associated with each of said wheels or disks, each gripping-plate operatively connected with one of said sliding blocks, whereby the plates are moved when the driven shaft is rotated, each of said plates having two gripping ends, one adapted to grip the rim of the wheel and rotate it in one direction and the other adapted to grip the rim of the wheel and rotate it in an opposite direction, said gripping ends being brought into operation by a lateral movement of said plate, a rod or the like connected with each of said gripping-plates, a sleeve through which said rod passes, a spring on each side of said sleeve and bearing thereagainst, one end of each spring being connected with said rod, a rock-shaft with which each of said sleeves is connected and a controlling-lever connected with said shaft, the whole so constructed that the driven shaft may be controlled independent of said driving-shaft.
